(57) **CLAIM**

The ornamental design for a door handle, as shown and described.

DESCRIPTION

FIG. 1 is a front, top, left side perspective view, of a door handle, in accordance with my new design;

FIG. 2 is a top plan view thereof;

FIG. 3 is a front elevational view thereof;

FIG. 4 is a bottom plan view thereof;

FIG. 5 is a left side elevational view thereof;

FIG. 6 is a right side elevational view thereof;

FIG. 7 is rear elevational view thereof;

FIG. 8 is a front, top, left side perspective view of a door handle, in accordance with a second embodiment of my new design;

FIG. 9 is a top plan view thereof;

FIG. 10 is a front elevational view thereof;

FIG. 11 is a bottom plan view of thereof;

FIG. 12 is a left side elevational view thereof;

FIG. 13 is a right side elevational view thereof;

FIG. 14 is rear elevational view thereof;

FIG. 15 is a front, top, left side perspective view of a door handle, in accordance with a third embodiment of my new design;

FIG. 16 is a top plan view thereof;

FIG. 17 is a front elevational view thereof;

FIG. 18 is a bottom plan view thereof;

FIG. 19 is a left side elevational view thereof;

FIG. 20 is a right side elevational view thereof; and,

FIG. 21 is rear elevational view thereof.

The broken lines shown represent unclaimed subject matter and form no part of the claimed design.

1 Claim, 15 Drawing Sheets
